UNITED STATES PATENT OFFICE.

ARCHIE J. GALVIN, OF CLEVELAND, OHIO.

SEWER CONSTRUCTION.

No. 882,941.

Specification of Letters Patent. Patented March 24, 1908.

Application filed August 3, 1906. Serial No. 329,012.

To all whom it may concern:

Be it known that I, ARCHIE J. GALVIN, a citizen of the United States, resident of Cleveland, county of Cuyahoga, and State of

5 Ohio, have invented a new and useful Improvement in Sewer Construction, of which the following is a specification, the principle of the invention being herein explained and the best mode in which I have contemplated 10 applying that principle, so as to distinguish it from other inventions.

My invention relates to the construction of conduits for sewer or other purposes out of reinforced concrete.

15 Such invention relates particularly to the construction of approximately circular or arched conduits and may be utilized with equal benefits, in the way of possibilities of rapid erection and of efficiency and durability when erected, in the building of arched structures of any sort whatever.

Said invention consists of means herein-after fully described and specifically pointed out in the claims.

25 The annexed drawing and the following description set forth in detail certain means embodying the invention, such disclosed means constituting but one of various mechanical forms in which the principle of the 30 invention may be used.

In said annexed drawing:—Figure 1 represents diagrammatically in transverse cross-section a form of reinforced-concrete sewer or conduit construction; Fig. 2 is a similar 35 cross-section of a conduit constructed in accordance with my invention; and Fig. 3 is a perspective view of such a conduit with a portion broken away.

The general type of conduit construction, 40 a specific modification of which forms the subject matter of this present invention, it should be explained has been already described in my pending application for U. S. Letters Patent on improvements in sewer construction, filed March 12, 1906, Serial No. 305,466. As there stated the principle of construction followed in such type of conduit, what ever the form of the latter, is the use therein of 45 separate molded blocks designed to occupy 50 specific positions in the completed structure and having embedded therein in the process of making, the reinforcing material that it has been found so desirable to use in connection with concrete or like materials to resist tension strains. This reinforcing material, which may be of any approved form, is

disposed in each particular block in proper position to fortify such block against the strains to which it will be subjected in the completed structure.

60 As being the simplest exemplification of the above principle of construction, I have described in the above application a rectangular sewer. A conduit or sewer of this form, as there pointed out, is preferable where the dimensions are but moderate, for it is both much easier to erect than is the arch form, the use of arch centering being done away with, and proper tamping of the earth about the walls is better insured. Obviously, however, for conduits of large size the rectangular form is not so well suited, inasmuch as a disproportionate amount both of concrete and reinforcing material is required, particularly for the upper transverse blocks.

70 To adapt the above described method of construction to the building of conduits of circular or arched form requires more than simply molding the blocks differently; it involves in addition thereto the consideration of how best to place the reinforcing material, since the bars, rods or other reinforcing elements cannot extend continuously around the arch if the latter is to be cut up into blocks. It is to the solution of this 75 problem that I have directed my attention in devising the structure now to be described.

Where the arch is monolithic, Fig. 1, or where, although it is built up of separate blocks, the reinforcing members are continuous across the arch, being embedded between the blocks or inserted in recesses or notches formed therein for such specific purpose, such reinforcing members are designed to pass through all the regions of tension of the 80 arch; for, while the concrete is capable of 85 withstanding compression to a high degree, its tensile stress is comparatively low. Now, obviously the exact location of the tension strains in the arch, whether of a conduit or 90 other structure, depends in part upon such structure's design, and in part upon the nature of the load to which it will be subjected. In the case of conduits, in particular, the effect of the load might vary considerably 95 depending upon the depth of such conduit and the character of the soil in which it was laid; yet in all it will generally be true that the regions of greatest tension normally exist in the intrados at the highest portion *b*, Fig. 1, of the arch and in the extrados at the haunches *c*, same figure, as the arch. In cer-

tain dispositions of the foundations, there would be another region of tension in the intrados near the springing line and where the foundations were poor or absent altogether 5 there might exist yet another such region, namely in the upper portion *d* of the invert. In the monolithic form of construction a continuous reinforcing member *e* would preferably pass through all these several regions 10 thus noted as being subjected to tensional strains. Intermediately, however, of adjacent regions of tension, as *c* and *d*, *c* and *b*, in the arch ring there will be other neutral regions, and, in fact, at the points *a* where the 15 so-called equilibrium polygon crosses the middle line of the arch ring there will be no tension whatever, either in the intrados or extrados of the arch. Accordingly, at these particular points *a* the use of tension or reinforcing members can be dispensed with and the arch structure rendered no less strong 20 than before; or, in other words, at these points the arch ring can be broken with impunity.

25 To carry out practically the conclusions just enunciated, each transverse section of my conduit would be made up of four separate blocks, Fig. 2, one *D* forming the invert, two *C* *C*, the respective side portions thereof, and 30 the remaining one *B* the crown. When the invert does not require to be reinforced, as in the case assumed and shown in the drawing, it may be built *in situ* either of concrete or brick, the latter material being preferred 35 by some engineers for at least the lining of this portion of the conduit. When reinforced, however, this block, as also the three others, are designed to be made in a plant or factory removed from the scene of construction 40 of the actual conduit, and the reinforcing material is embedded in such blocks in the process of their making. In the case of the invert block, the disposition of the reinforcing or tension member, as has been indicated 45 would be substantially horizontally across and near the upper surface of the same, the ends of the member being preferably recurved in order to give it a more secure anchorage, as also, and even more particularly, to facilitate the correct placing of 50 such member in the course of manufacturing the blocks. In the case of the lateral blocks *C* on the contrary such tension members *e*¹, Fig. 2, should lie near the extrados of the 55 arch, and substantially parallel therewith. The ends of these tension members are likewise recurved, as shown. In addition to these principal reinforcing members *e*¹, secondary reinforcing members *e*² are also advisedly employed, being disposed near, and 60 substantially parallel with, the inner faces of the blocks, which become the intrados of the completed arch, in order to strengthen such arch against lateral pressure from without. These members *e*² need not be so long 65 as members *e*¹. In the upper block *B* that forms the crown of the arch, the reinforcing members *e*¹ are disposed so as to lie in the intrados of the arch. They lie, in fact, very nearly horizontal, the curve of the arch at 70 this point being slight; and their ends are recurved for the purpose of more securely anchoring them as in the case of the other blocks. The character and number of such reinforcing members *e*¹ *e*² employed in each 75 of the respective blocks, of which the conduit is constructed, is of course immaterial and should depend upon the particular conditions to be met by such conduit structure. Thus, for the rods shown in the drawing, netting or stamped metal or other approved material may be substituted, the disposition thereof being the more important feature. So, also, two different forms of joint are shown, a smooth radial joint in Fig. 2 and a 80 dove-tailed joint in Fig. 3. Ordinarily the latter would be preferred. The main point however, is that they should be located approximately at the points where the equilibrium polygon crosses the middle line of the 85 arch ring.

By the means described I am enabled to build tubular, or otherwise arched, conduits as readily as rectangular ones, and at the same time conserve all the other advantages 90 inherent in the method of construction of which such means are an embodiment. Thus greater care can be exercised in mixing the concrete of which the conduit is ultimately to be constructed, and particularly 95 in the placing of the reinforcing material than is possible under the trying conditions of field work; and inspection of the finished blocks in the manner in which other structural materials are tested can be substituted 100 for the constant and, at the best, ineffective surveillance of workmen in the field. And, moreover, the completed structure is possessed of all the desirable characteristics of a 105 true monolithic arch, since the joints, being 110 wholly in the regions of compression and well cemented together are hardly to be regarded as breaks in the continuity of the arch ring, and the reinforcing members are placed to take up all tensional strains.

Having thus described my invention in detail, that which I particularly point out and distinctly claim, is:

1. An arch structure comprising the combination of blocks formed and disposed to bring the division lines or joints between adjacent blocks approximately at the points in the arch ring where the equilibrium polygon crosses the middle line of such ring.
2. An arch structure comprising the combination of blocks formed and disposed to bring the division lines or joints between adjacent blocks approximately at the points in the arch ring where the equilibrium polygon crosses the middle line of such ring, said 130

- blocks being formed of concrete with tension members embedded therein.
3. An arch structure, comprising the combination of blocks formed and disposed to bring the division lines or joints between adjacent blocks approximately at the points in the arch where the equilibrium polygon crosses the middle line of such ring, said blocks being formed of concrete with reinforcing members embedded therein in their several regions of tension.
4. An arch structure composed of an invert portion, lateral portions, and a crown portion, the division lines or joints between such portions being located approximately at the points where the equilibrium polygon crosses the middle line of the arch ring.
5. A concrete arch structure composed of an invert portion, lateral portions, and a crown portion, said portions being reinforced in their respective regions of tension, and the division lines or joints between said portions being located approximately at the points where the equilibrium polygon crosses the middle line of the arch ring.
6. An arch structure composed of an invert portion, lateral portions, and a crown portion, the division lines or joints between such portions being located approximately at the points where the equilibrium polygon crosses the middle line of the arch ring, and each of such portions comprising a block formed of concrete and having reinforcing members embedded therein in its respective region of tension.

Signed by me, this 14th day of July, 1906.

ARCHIE J. GALVIN.
